UNITED STATES PATENT OFFICE.

JOHN W. GIBBS, OF CHARLESTON, ILLINOIS.

WEEDER.

Application filed November 13, 1924. Serial No. 749,744.

The present invention relates particularly to a weeder adapted for attachment as an auxiliary to hand cultivators of any suitable type, although the principles involved 5 may of course be applied to weeder structures in general. According to the invention I provide a plurality of cutting edges which may be selectively employed and in order to prevent rapid drying out of the 10 ground I provide a roller which is adapted to cooperate with the cutting edge employed. My structure allows of various working combinations which will be evident from the following detailed description 15 with reference to the accompanying drawings in which:

Fig. 1 is a side elevation of the weeder as attached to a hand cultivator frame,

Fig. 2 is a top plan view of the weeder, 20 Fig. 3 is a longitudinal section of same on line 3—3 of Fig. 2 and,

Fig. 4 is an end view of the weeder showing the knives in a different relation.

Referring to the drawings, 1 represents 25 the wheel of the cultivator and 2 the handles carried thereby. A depending tongue 3 is provided and is attached by bolts 4 to the handles and is braced by means of a member 5 attached thereto at 6. At its 30 lower end the tongue consists in the usual manner of two spaced elements as shown at 7, Fig. 2. The U-frame 8 which serves for supporting the weeder elements is adapted to be attached to the depending tongue elements 7 by means of a bolt 9 insertable therebetween. I also provide a coupling element 10 having the claws 11 which cooperate with the tongue in order to provide a 35 rigid connection between it and the frame 8. As will be seen from the drawings the member 10 is held by bolt 9 with its claws 11 resting on the edge of the frame element 8 so that no relative twisting movement between the two is possible. Pivoted to the 40 frame 8 near its shoulders by means of bolts 12 are the arms 13 and 14 which are preferably integral with the horizontal knives 15 and 16 respectively. As will be seen the arms 13 are longer than arms 14 45 and the knife 15 is longer than the knife 16 and both of the latter are provided with double edges. In its operative position the frame 8 is of course substantially horizontal and as will be seen from Figs. 1 and 3 one 50 of the knives is disposed above frame 8 and the other below the same. The position of

the knives is determined by the rigid spacers 17 and 18 connecting the frame with arms 13 and 14 respectively. In order to vary the angular position of the arms 13 and 14 relative to the frame 8 the spacers 17 and 18 are provided with a plurality of spaced apertures whereby by means of the bolts 19 and 20 they may be variably attached to the respective arms. Pivoted at 55 the end of the frame 8 by means of bolts 21 are the depending arms 22 attached at their other ends to the axle 23 of a roller 24. The bolts 21 also serve for attaching arms 17 to the frame 8.

The device is shown in Fig. 1 with the knife 15 in working position, that is, in a lower position relative to the frame 8, and thus its forward edge is in a position to effect a sub-surface cutting action. At the 60 same time roller 24 depends from frame 8 in a position immediately behind the knife 15. Now if it is desired to adjust the weeder for a narrower swathe the bolt 9 is loosened and the frame 8 turned through 65 180°. This will bring the knife 16 into operating position and at the same time by force of gravity the roller 24 will come into a position to cooperate with this knife. If 70 it is desired to accomplish a plural weeding 75 action the knives may be brought into the parallel position shown in Fig. 4. The fact that arms 14 are shorter than arms 13 allows this relative positioning of the two 80 knives; otherwise, and if it is not desired to 85 use double cutting edges, the two sets of arms may be made of equal length or in any desired proportion.

It is evident that with the weeder assembled in the manner described only the forward edge of each of the knives will come 90 into use. However, when these edges become dull, by merely removing bolts 19 and 20 the arms 13 and 14 may be swung so that the disposition of knives 15 and 16 95 relative to the frame 8 is reversed and thus the other edge of each of the knives will be 100 presented in working position.

Having thus described my invention I 105 claim:

1. The combination of a weeder comprising a plurality of horizontal knives, a common carrying-member for said knives, said carrying-member being swingable on a horizontal axis transverse to the longitudinal direction of the knives for bringing the latter selectively into working position, and 110

a roller suspended from said frame behind said knives.

2. The combination of a weeder comprising a plurality of horizontal knives, a common carrying-member for said knives, said carrier member being swingable on a horizontal axis transverse to the longitudinal direction of the knives for bringing the latter selectively into working position, and a

10 roller pivotally suspended from said frame behind said knives, whereby upon swinging said frame on said transverse axis said roller will fall into position behind the knife swung into operative position.

15 3. A weeder comprising a horizontal frame, transverse knives disposed on opposite sides thereof, angularly projecting arms at the extremities of said knives, the ends of said arms being pivoted to said frame, and releasable braces between said frame and said arms whereby the upper knife may be swung on its pivots to operative position below said frame, and the lower knife swung on its pivots to inoperative position above said frame.

20 4. A weeder comprising a plurality of

two-edged horizontal knives, a common carrying member for said knives, said carrying member being swingable on a horizontal axis transverse to the longitudinal direction of the knives, and said knives being swingable about an axis parallel to themselves, whereby a selected knife and a selected edge thereof may be brought into working position.

25 5. A weeder comprising a pair of knives each consisting of a blade portion and angularly disposed end portions, the end portions of one knife being longer than those of the other knife, a frame, means for pivoting the ends of said arms to said frame on a single axis parallel to the blades, and releasable braces between said frame and said knives for holding either knife down in operative position and the other up in inoperative position, or for holding both knives down in operative position.

30 The foregoing specification signed at Charleston, Illinois, this 20th day of October, 1924.

40 JOHN W. GIBBS.
